AXMINSTER LOOM ROPE STOP MOTION

Frank Darienzo, Amsterdam, N. Y., assignor to
 Bigelow-Sanford Carpet Co., Inc., Thompson-
 ville, Conn., a corporation of Massachusetts

Application September 14, 1937, Serial No. 163,792

2 Claims. (Cl. 139—336)

This invention relates to Axminster looms and particularly to novel mechanism for stopping the loom automatically when the needle reciprocating rope breaks.

5 In Axminster looms it is customary to insert the weft by a needle which is reciprocated into and out of the shed by a rope or similar flexible driver, power-driven by being wound about an oscillating drum or scroll. Breakage of the rope 10 while the loom is running is not unusual, resulting in breakage of the loom, damage to the fabric and possible injury to the operative.

The object of the present invention is to provide mechanism to stop the loom automatically 15 upon such rope breakage and to that end, as will appear, I provide a follower engaging the rope and preferably tensioning the same, which follower may be one of the pulleys commonly employed to guide the rope, so connected by linkage 20 to the starting lever as to stop the loom automatically when the rope breaks. My novel stop mechanism may also desirably operate to take up the slack as the rope stretches during use and to stop the loom automatically when the 25 stretch has become excessive, indicative that the rope should be replaced.

These and further objects and advantages of my invention will appear from a more detailed description thereof, taken with accompanying 30 drawings, in which:

Fig. 1 is a perspective view of a needle drive having my novel automatic stop mechanism embodied therein;

Fig. 2 is an elevation view, partly in section, 35 taken on the line 2—2 of Fig. 1;

Fig. 3 is an elevation view, similar to Fig. 1, of a modified form of my invention; and

Fig. 4 is a vertical section on the line 4—4 of Fig. 3.

40 My invention may be embodied in any loom of the Axminster type in which the weft is inserted by a needle, reciprocated by a rope or other flexible driver. Such weft inserting mechanism is illustrated diagrammatically in Fig. 1 45 wherein the weft 1, unwound from a suitable supply package, passes through the eye of a needle 3 slidably received and guided by the needle rail 5. The needle is connected by bracket 7 to a flexible driver 9 which may be a rope, chain, 50 or the like, in this instance a rope, guided about a pulley 11 near the shed and another similar pulley (not shown) at the opposite end of the needle rail. The rope is reciprocated by an oscillating drum or scroll winder 10, driven from 55 the loom shaft by mechanism, not shown,—about

which winder the rope 9 winds and unwinds, as indicated, to reciprocate the needle into and out of the shed. All of the foregoing mechanism is of the usual character in Axminster looms and requires no further description as it forms no 5 part of the present invention.

A starting lever 15 connects the loom to a suitable source of power. The lever illustrated typifies any desired form of starting and stopping element, such as a clutch lever, a belt shifting 10 lever, an electric switch lever or push button, or other element, as desired. When a lever is used, as shown, it may be guided between its full line "on" position and its dotted line "off" position by a slotted bracket 17 having a notch 15 19 adapted to hold the lever in its "on" position. The spring 21 indicates that the element is shifted to its "off" position automatically when it is moved out of the notch 19. Any other type of starting element may, of course, be used. 20

In the embodiment of my invention illustrated in Fig. 1, the pulley 11 is rotatably mounted on a shaft 25 formed on one end of a bar 27 which is pivoted to the frame of the machine at 29. A spring 31, attached at 33 to the frame of the 25 machine and at 35 to the bar 27 yieldingly urges the bar in a clockwise direction about pivot 29, as viewed in Fig. 1, and this movement is limited by an elongated slot 37 in a bracket 39 attached to the loom frame, into which slot projects the 30 end of shaft 25, as shown.

The end of bar 27 opposite that formed into the shaft 25 carries, pivotally secured to it at 41, a tie rod 43, secured at 45 to a lug 47 (Fig. 2) projecting from a hub 49 rotatably mounted on 35 a stud shaft 50. The hub 49 carries a projecting finger 51 adapted to bear downwardly on a rod 53 projecting from a rotatably mounted hub 55. The hub also carries a projecting arm 57 engaging the handle of the starting lever 15 and 40 adapted to move the same out of the notch 19 as indicated in dotted lines in Fig. 2.

With the mechanism constructed as above described, it is apparent that during the normal running of the loom the pulley 11 tensions the 45 rope 9 by reason of the spring 31 urging clockwise rotation of the bar 27 as viewed in Fig. 1. If the rope should break, the bar 27 will swing about the pivot 29 in the amount permitted by the elongated slot 37, thus, through tie rod 43, 50 rotating hub 49 and moving finger 51 and rod 53 downwardly. The resultant movement of arm 57 moves lever 15 out of notch 19 and spring 21 (Fig. 1) immediately shifts the lever to its off 55 position, thereby stopping the loom.

As a modification of the preferred form of my invention which has been described above, I have disclosed in Figs. 3 and 4 a construction which, by employing an auxiliary pulley, obviates the 5 necessity for a special mounting for the main pulley 11.

In Fig. 3 the pulley 11a, around which rope 9a runs, may be mounted in a fixed bearing 101 in the customary manner. The auxiliary pulley is 10 indicated at 103 and, as shown in Fig. 4, this pulley is preferably mounted beneath the lower course of rope 9a on a shaft 107 pivoted at 109 to a bracket 111 depending from the loom frame. A weight or spring 112, attached to an extension 15 of shaft 107, urges clockwise rotation of the shaft about pivot 109 and the opposite extremity of the shaft is received in an elongated slot 115 formed in bracket 111 adapted to guide and to limit the vertical swinging movement of shaft 107 about pivot 109.

A link 113, loosely mounted on shaft 107, is pivoted at 45a to a lug 47a projecting from a hub 49a rotatably mounted on stud shaft 50a, the arrangement being identical with the similarly numbered parts in the preferred embodiment illustrated in Fig. 1. Hub 49a similarly carries a finger 51a which operates through arm 57a to shift lever 15a out of its notch and to its off position through the influence of spring 21 just as 30 in the preferred embodiment above described.

It will be noted that in both embodiments of my invention above described, the follower or pulley which actuates the stop mechanism when the rope breaks, also so applies tension to the 35 rope as to take up the slack as the rope stretches during use. If desired, that feature of my invention may be dispensed with, particularly where a non-stretching driver, such as a chain, is employed. However, it is a desirable feature where 40 a stretchable driver is used and it will be noted that with such a construction the loom will be stopped automatically when the stretch has be-

come excessive, indicative that the rope should be discarded.

It will be apparent to those skilled in loom construction that other linkage of a similar nature may readily be employed to connect a follower 5 engaging the needle driving rope with mechanism adapted to connect and disconnect the loom with a source of power. Whereas I have found that the embodiments illustrated are best adapted for my purpose yet my invention is not to be limited 10 thereto or to any other details set forth herein except as indicated in the appended claims.

I claim:

1. In an Axminster loom, the combination with a weft inserting needle, a flexible driver for reciprocating the same into and out of the shed and a starting element adapted to start and to stop the loom, of a movably mounted member having a follower engaging the driver so that movement is imparted to the member when the 20 driver breaks and linkage connecting the said member directly to the starting element so that the said movement of the member is imparted through the linkage to the starting element whereby to stop the loom automatically and immediately upon breakage of the driver.

2. In an Axminster loom, the combination of a weft inserting needle, a flexible driver for reciprocating the same into and out of the shed, a needle rail guiding the needle during its reciprocation, a pulley at each end of the needle rail around which the driver passes, a pivotally mounted bracket supporting one of said pulleys, means yieldingly urging rotation of said bracket about its pivot to tension the driver as it passes 35 about said pulley, a starting element adapted to start and to stop the loom, means releasably holding the element in its on position to run the loom, and linkage connecting said bracket with the starting element to release the latter and 40 stop the loom automatically when the driver breaks.

FRANK DARIENZO.
